UNITED STATES PATENT OFFICE

EDWIN J. MERKLEY, OF JASPER, INDIANA, ASSIGNOR TO LOUIS T. KOERNER, OF JASPER, INDIANA

HAT AND COAT HOLDER

Application filed August 21, 1929. Serial No. 387,437.

The present invention is directed to improvements in hat and coat holders.

The primary object of the invention is to provide a device of this character which can be easily and quickly attached to an automobile in order that a hat can be conveniently supported or a coat or other garment suspended within the automobile.

Another object of the invention is to provide a device of this character so constructed that the hat holding loop will be properly maintained with respect to the roof of the car, said loop being swingable so that the hat can be readily engaged therewith or removed therefrom.

Another object of the invention is to provide a device of this character which is simple in construction, efficient in operation, durable, and one which can be manufactured at a very small cost.

With these and other objects in view, this invention resides in the novel features of construction, formation, combination and arrangement of parts to be hereinafter more fully described, claimed and illustrated in the accompanying drawing, in which:

Figure 1 is a side elevation of the device, showing the same mounted in an automobile.

Figure 2 is a top plan view of the device.

Figure 3 is a detail sectional view through the same.

Figure 4 is a sectional view on the line 4—4 of Figure 3.

Referring to the drawing, 1 designates the roof of a motor vehicle and 2 the front bar frame and to which the device is preferably secured. The holder comprises a plate 3 which is secured to the bar 2 by securing devices 4, said plate having its upper end provided with a transversely curved flange 5 which terminates in spaced stops 6, the purpose of which will be later explained. The plate 3 has secured thereto in any approved manner a hook 7 which serves to suspend a garment when desired.

The plate is provided near its upper end with a pair of rearwardly extending ears 8 in which are supported shafts 9, said shafts 50 having engaged thereon a coil spring 10,

the terminals 11 of which bear against the plate 3 and plate 12, the plate 12 having ears 13 carried thereby which are pivotally connected with the shafts 9 and are embraced by the ears 8. The plate 12 is reduced, as indicated at 13, the reduced portion thereof having sleeves 14 turned thereon and in which are engaged the arms 15 of the hat supporting loop 15'. The arms 15 are firmly connected to the plate 12 so that the loop 15' will be held firmly in position.

It will be obvious that when it is desired to apply or support a hat it is only necessary to grasp the loop and pull the same downwardly whereupon the crown of the hat may be passed through the loop and the loop released so that the hat will be elevated and firmly held against accidental displacement. Obviously, the spring 10 will maintain the loop in a horizontal position but will permit ready lowering of the loop in order that the hat can be removed or replaced. The upward swinging movement of the plate 12 will be obviously limited when the same contacts with the stops 6.

From the foregoing, it is thought that the operation and many advantages of the herein described invention will be apparent to those skilled in the art without further description and it will be understood that various changes in the size, shape, proportions and minor details of construction may be resorted to without departing from the spirit or sacrificing any of the advantages of the invention.

What is claimed is:

1. A device of the class described comprising a plate having a curved flange carried by its upper end terminating in downwardly disposed stops, said plate having ears carried thereby, a second plate having ears carried thereby, a shaft passable through the ears of said plates, a coil spring encircling the shafts and having one terminal engaged with the first named plate and the other terminal engaged with the second named plate, sleeves carried by the second named plate, a hat sustaining loop having arms engaged in said sleeve, said spring serving to normally urge the second named plate upwardly, the upward 100

movement thereof being limited by said stops.

2. A device of the class described comprising a plate, stops connected with the plate, a hook carried by the plate, a second plate pivotally connected with the first named plate and having sleeves carried thereby, a hat sustaining loop having arms carried thereby and engaged in said sleeve, and means for urging the second named plate upwardly, the upward movement thereof being limited by said stops.

10 In testimony whereof I affix my signature.
EDWIN J. MERKLEY. [L. S.]
